UNITED STATES PATENT OFFICE.

ALEXANDER R. FORDYCE, OF NEWARK, NEW JERSEY.

METALLIC LATHING.

SPECIFICATION forming part of Letters Patent No. 585,563, dated June 29, 1897.

Application filed April 5, 1897. Serial No. 630,680. (No model.)

To all whom it may concern:

Be it known that I, ALEXANDER R. FORDYCE, a citizen of the United States, and a resident of Newark, in the county of Essex 5 and State of New Jersey, have invented certain new and useful Improvements in Metallic Lathing, of which the following is a full, clear, and exact description, such as will enable those skilled in the art to which it appertains to make and use the same, reference being had to the accompanying drawings, which form a part of this specification.

This invention relates to improvements in metallic lathing or skeletons which are used 15 in the construction of fireproof walls, ceilings, partitions, &c.

It relates more particularly to that class of skeletons which is termed "metallic lathing," which when attached to suitable supports 20 forms the foundation for the filling that goes to make the body of such constructions.

It relates especially to improvements in that kind of metallic lathing that is made by slitting a sheet of metal and turning back the 25 edges of the slits to provide openings for the passage of the filling and also to form keys. In lathing of this character as heretofore made the keys generally have been turned out from the plate on the same side, thereby 30 leaving the other side comparatively smooth and keyless. When lathing of the latter description is used, the filling placed on the smooth side has to depend on that part of the same that enters the apertures in the 35 plate for support. This is objectionable, as the filling has very little tenacity in its green state and would be very apt to be displaced on the plain side of the plate, as the comparatively small quantity of filling entering the 40 apertures would not be sufficient to support the main body, and, furthermore, when lathing having a plain side is placed with its plain side against a flat surface the filling cannot pass through the apertures to any extent to 45 form a sufficient clench. It has been sought to overcome this last difficulty by corrugating the lathing. In this last instance the corrugations form pockets into which the filling passes through the apertures and thereby 50 forms a clench. It has been found to be very difficult to make a lathing of this character,

especially when the keys have considerable size, as the latter cannot be bent easily to conform with the corrugations. In the invention in the present instance it is proposed 55 to overcome these difficulties by turning the keys out from both sides of the plate, thereby forming a reversible lathing having both faces alike.

The invention consists in the novel construction, such as will be hereinafter fully described, pointed out in the appended claims, and illustrated in the accompanying drawings.

In the accompanying drawings, in which 65 similar letters of reference designate corresponding parts, Figure 1 is a plan view of a section of lathing embodying the invention. Fig. 2 is a sectional view on the line 2 2 of Fig. 1. Fig. 3 is a similar view on the line 70 3 3. Fig. 4 is a sectional view showing the lathing applied to a flat surface and embedded in a filling.

In carrying out the invention a metallic plate A of the required dimensions is provided with parallel ribs a a, extending its entire length. These ribs serve to strengthen 75 the plate, so that the latter will be able to sustain any considerable stress that may be applied to the same in a direction at right angles to the ribs. These ribs also divide the plate into panels B B.

In each of the panels B B a row of apertures b b is formed. Each aperture is substantially in the form of an elongated isosceles triangle. Their relative arrangement is such that the apex of one aperture points toward the base of the adjacent aperture in the same row. An aperture is formed by slitting the panel and turning back the edges of the metal to form the flanges b' and b² and also the spur b³. The flanges b' and b² are irregular in form and approach each other at their outer edges to form a key having irregular sides.

The apertures of the several rows are arranged so that those of one row break joint with those of an adjacent row, and also so that the apertures in one row have their apices pointing in one direction while the apertures in an adjacent row have their apices pointing 95 in the opposite direction, and, furthermore, 100

the rows of keys alternately project from opposite sides of the plate, so that both sides have the same formation.

In the construction hereinbefore described 5 a lathing or skeleton of considerable thickness is produced which is especially adapted to form the foundation of a partition where considerable strength is required and in which the skeleton must have considerable depth to 10 enable it to properly support the filling when the partition has considerable thickness. This is secured by the plate retaining considerable of its original structure and also by the keys projecting from opposite sides of the plate, 15 and the peculiarly-shaped apertures, which will allow the filling to secure a strong and effective clench. The construction also provides a lathing particularly adapted to be used in applying a plastic material to flat surfaces. 20 When the lathing is placed against such a surface, the projecting keys prevent the main body of the plate from coming in contact with said surface and thereby allows the plastic filling to pass behind the lathing and thereby 25 secure a proper clench.

Having thus described my invention, what I claim, and desire to secure by Letters Patent, is—

1. A lathing consisting of a metallic plate 30 having an elongated aperture formed therein and the metal displaced by the formation of said aperture turned back to form two irregular elongated flanges, the said flanges constituting a substantially continuous collar forming a key having irregular sides. 35

2. A lathing consisting of a metallic plate having apertures formed therein, the metal displaced by the formation of said apertures turned back to form flanges, the said flanges arranged in rows projecting alternately from 40 opposite sides of the plate, and also arranged so that the flanges of one row break joint with and overlap the flanges of an adjacent row.

3. A lathing consisting of a metallic plate having apertures formed therein, the metal 45 displaced by the formation of said apertures turned back to form flanges, the said flanges projecting from the body of the plate to form keys, the said keys arranged in rows so that those of one row break joint with and overlap 50 those of an adjacent row, and the said keys also arranged so that alternate rows of the same project from opposite sides of the plate.

4. A lathing consisting of a metallic plate having elongated apertures formed therein, 55 the metal displaced by the formation of each of said apertures turned back to form two irregular elongated flanges, the said flanges forming a key with irregular sides, and the said keys arranged in rows projecting alternately from opposite sides of the plate, and also arranged so that the keys of one row break joint with and overlap the keys of an adjacent row.

In testimony whereof I hereunto affix my 60 signature in the presence of two witnesses.

ALEX. R. FORDYCE.
